UNITED STATES PATENT OFFICE.

JOSEPH EHRHARD, OF CURTIS, OKLAHOMA.

WRENCH.

1,129,966.

Specification of Letters Patent.

Patented Mar. 2, 1915.

Application filed April 10, 1914. Serial No. 830,899.

To all whom it may concern:

Be it known that I, JOSEPH EHRHARD, a citizen of the United States, residing at Curtis, in the county of Woodward and State of Oklahoma, have invented certain new and useful Improvements in Wrenches, of which the following is a specification.

My invention relates to wrenches, the more particular purpose of my improvement being to produce a wrench of comparatively simple construction and admitting of a great variety of uses.

My invention further relates to means for rendering the wrench adjustable quickly and yet accurately.

My invention contemplates various other advantageous features, for the purpose of improving the general efficiency of the wrench.

Reference is made to the accompanying drawings forming a part of this specification, and in which like letters indicate like parts.

Figure 1 is a side elevation of my improved wrench complete, and showing in full and dotted lines, respectively, various movable parts as occupying different positions. Fig. 2 is a central section through the wrench complete. Fig. 3 is a top view, showing the wrench partly in plan and partly in section. Fig. 4 is a side elevation, showing the wrench as used without the slide. Fig. 5 is a section, on the line 5—5 of Fig. 1, looking in the direction of the arrow.

Two arms are shown at 3, 4, the arm 4 carrying a bearing 5, and extending through this bearing and through the adjacent end of the arm 3 is a bolt 6. An adjusting screw 7 is carried by the arm 3 and used as a limiting stop for preventing excessive travel of the two arms 3, 4 relatively to each other. A leaf spring 3^a is secured by a fastening 3^b to the arm 3, and is used for pressing the arms apart, and thus holding them in a predetermined normal relative position. The arms 3, 4 are provided with gripping surfaces 8 and with lugs 9 bounding these gripping surfaces and serving as limiting stops for the articles to be held between the gripping surfaces 8. The arm 3 is provided with a groove 10. A slide 11 is carried by the arm 3, and fits into the groove 10, being provided with a tongue 12 (see Fig. 5) for this purpose. The slide 11 is provided with an opening 13. A bolt 14, provided with a head 15, extends into this opening, through

a hole 14^a, and engages a nut 16 lodged within this opening.

A hood 17 is fitted upon the slide 11, and is provided with a sloping wall 18, mating a sloping surface 18^a with which the slide 11 is provided, as indicated in Fig. 2. The hood 17 carries a strap 19 extending around the arm 3. By turning the bolt 14 by aid of its head 15, the slide 11 and hood 17 are adjusted relatively to each other, and if the bolt 14 be turned far enough, the sloping surface 18^a of the slide 11 is drawn against the mating surface 18 of the hood, so that the strap 19 is jammed tightly against the adjacent portion of the arm 3. This clamps the slide 11 rigidly upon the arm 3. Therefore, the operator by loosening the bolt 14 and adjusting the slide 11 and hood 17 bodily along the arm 3, and then tightening the bolt 15, may clamp the slide 11 in any desired position along the groove 10.

The hood 17 is provided with a laterally extending portion 20, serving as a bearing. This bearing carries a pin 22, and mounted upon this pin is a thumb lever 21. A spring 23 engages this thumb lever and also engages the adjacent wall of the hood 17, as may be understood from Fig. 3. The thumb lever 21 is provided with a portion 24 serving as a pawl. The arm 3 is provided with a number of teeth 25 arranged in a straight row, and together constituting a ratchet, to be engaged by the pawl just mentioned.

Normally, under pressure of the spring 23, the thumb lever 21 is maintained in such position that the pawl 24 engages two of the teeth 25. The operator, however, by pressing upon the thumb lever 21 can disengage the pawl 24 from the teeth 25. This being done, the slide 11 and hood 17 can be moved in either of two directions, provided of course the bolt 14 is not tightened. If the operator does not press upon the thumb lever 21, and the bolt 14 is not tightened, the hood 17 and slide 11 may be moved to the left according to Figs. 1, 2 and 3, but can not be moved to the right.

A pair of side bars 26 are each provided adjacent its ends with a number of holes 27, and bolts 28 are provided for fitting into these holes. Engaging the bolts 28 are nuts 28^a for holding the bolts in position.

The arms 3, 4 are provided each with a number of holes 29, 30, and the bolts 28 may be fitted into these holes. The slide 11 is likewise provided with a hole through

which one of the bolts 28 may be extended, as indicated in Fig. 2.

If desired, the side bars 26 may be connected with the arm 4 and with the slide 11, as indicated in Figs. 1 and 2. Again, the side bars 26 may be connected directly with the arm 3, as indicated in Fig. 4.

The arm 4 is provided upon its lower or outer face with a number of notches 31, 10 and either of the bolts 28 may be fitted into any one of these notches, as may be understood from Fig. 4. If the side bars 26 be connected with the arm 3, as indicated in Fig. 4, by one of the bolts 28, the other bolt 15 28 may be brought into any one of the notches 31.

By shifting the bolts 28 into different holes of the arms 3 and 4, and also into different notches of the arm 4, the wrench 20 may be given a variety of different adjustments. Again, by connecting the side bars 26 with the arm 4 by aid of some one of the holes 29, and also connecting the side bars with the slide 11, as indicated in Figs. 25 1 and 2, the range of adjustments for the wrench is still further increased. The gripping surfaces 8 may thus be quickly and accurately brought to fit any object to which they can be applied.

30 By arranging parts substantially as indicated in Figs. 1 and 2, and then tightening the bolt 14, the gripping surfaces 8 may be rendered for the time being immovable relatively to each other.

35 I do not limit myself to any particular use for my wrench, as it may be employed in various arts and for an infinite variety of different purposes.

Neither do I limit myself to the precise 40 mechanism shown, as variations may be made therein without departing from the spirit of my invention.

Having thus described my invention, what I claim as new and desire to secure by Letters Patent is as follows:

1. In a wrench, the combination of a pair of arms provided with gripping surfaces and movable relatively to each other, an 50 adjusting screw carried by one of said arms for engaging the other arm, a spring for pressing the arms apart, a pair of side bars, and bolts carried by said side bars, the said arms being each provided with a plurality of means for engagement by said bolts whereby 55 the side bars may be adjustably connected with said arms.

Copies of this patent may be obtained for five cents each, by addressing the "Commissioner of Patents, Washington, D. C."

2. In a wrench, the combination of a pair of arms movable relatively to each other and provided with gripping surfaces, one of said arms being provided with a groove and having a slide provided with a portion extending into said groove, means controllable at the will of the operator for locking said slide in various positions of adjustment relative to the arm carrying it, and side bars 60 connected with said slide and with the arm mating the arm upon which said slide is mounted.

3. In a wrench, the combination of a pair of arms movable relatively to each other, a 70 pair of side bars pivotally connected to one of said arms, a slide engaging the other of said arms and pivotally connected to said side bars, a hood engaging said slide and provided with a portion encircling the arm carrying said slide, and mechanism connected with said slide and with said hood for moving said slide and said hood relatively to each other in order to cause said portion encircling the arm carrying the slide 80 to bind against the arm and thus secure the slide rigidly thereupon.

4. In a wrench, the combination of a pair of arms movable relatively to each other, a 85 slide mounted upon one of said arms, a pair of side bars pivotally connected with said slide and with the other of said arms, and means controllable at the will of the operator for locking said slide in different positions along the arm which carries it. 90

5. In a wrench, the combination of a pair of arms movable relative to each other, a slide mounted upon one of said arms, a pair of side bars pivotally connected with said slide and with the other of said arms, a 95 hood engaging said slide and provided with a portion encircling the arm carrying the slide, mechanism connected with said slide and with said hood for moving the slide and hood relatively to each other, the said arm carrying the slide being provided with teeth, and a spring controlled lever carried by the hood and having a portion serving as a pawl for engaging said teeth.

In testimony whereof I have signed my 105 name to this specification in the presence of two subscribing witnesses.

JOSEPH EHRHARD.
